CLAIM

We claim the ornamental design for a gaming services robot, as shown and described.

DESCRIPTION

FIG. 1 is a front perspective view of a gaming services robot showing our new design according to a first embodiment;

FIG. 2 is a front elevation view thereof;

FIG. 3 is a right-side elevation view thereof, with the left-side elevation view being a mirror image thereof;

FIG. 4 is a rear elevation view thereof;

FIG. 5 is a top plan view thereof;

FIG. 6 is a front perspective view of a gaming services robot showing our new design according to a second embodiment;

FIG. 7 is a front elevation view thereof;

FIG. 8 is a right-side elevation view thereof, with the left-side elevation view being a mirror image thereof;

FIG. 9 is a rear elevation view thereof;

FIG. 10 is a top plan view thereof;

FIG. 11 is a front perspective view of a gaming services robot showing our new design according to a third embodiment;

FIG. 12 is a front elevation view thereof;

FIG. 13 is a right-side elevation view thereof, with the left-side elevation view being a mirror image thereof;

FIG. 14 is a rear elevation view thereof; and,

FIG. 15 is a top plan view thereof.

The dashed broken lines in the figures illustrate portions of the gaming services robot that form no part of the claimed design.
